UNITED STATES PATENT OFFICE.

CARL RAUHE, OF DUSSELDORF, GERMANY.

ARTIFICIAL DENTURE.

1,098,331.

Specification of Letters Patent.

Patented May 26, 1914.

Application filed August 15, 1913. Serial No. 784,917.

To all whom it may concern:

Be it known that I, CARL RAUHE, a citizen of the German Empire, residing at Dusseldorf, Germany, have invented certain new and useful Improvements in or Relating to Artificial Dentures, of which the following is a specification.

My invention relates to improvements in artificial dentures but more particularly to the manufacture of the suction devices for the same.

The object of my invention resides in a form for molding the suction-cavity on dental-plates and embedding the fastening button for the rubber disk thereon, which form may be freely withdrawn from the dental-plate after the embedding of the inserted button thereon, thus obviating the use of any sharp tool for removing the mold, preventing damage or deformation to the button. On the other hand the button has a finished bed for the reception of the rubber disk of such shape as to secure a correct setting of the latter.

In describing the invention in detail reference will be had to the accompanying drawing, forming part of the specification, and wherein like characters denote corresponding parts in the several views, in which:

Figure 1 is a face view of the molding form, Fig. 2 is a central cross-section of same. Fig. 3 is a cross section of the form fitted with stud- or button-insertion. Fig. 4 is a cross-section of the crown portion of a dental plate in which the button has been fixed.

The molding form or disk *b* (preferably of tin or such like metal) as shown in Figs. 1 and 2 has a recess fitting the head *a*² of the stud *a* to be inserted therein (Fig. 3) and having a cover *b*¹ while the larger foot-plate *a*³ of the stud (when inserted in the form *b*) lies close against the lower face of the form *b*, thus closing the recess.

The mounting of the new suction device is effected as follows: The form *b* with the inserted button *a* (Fig. 3) is placed on the plaster cast model in such manner that the large foot-plate *a*³ of the stud *a* lies upward

and is then pressed down with the thumb to 50 shape it roughly to the position it is to occupy. After the case is packed and the plate vulcanized in the usual manner the form *b* may be freely removed from the denture-plate, without the use of any instrument, inasmuch as the form *b* has no collar extending beneath the head *a*² of the stud or button *a*, (now attached to the denture-plate, Fig 4), and the rubber on packing the case cannot enter beneath the head *a*², owing 55 to the cover *b*¹ of the form *b* and the foot-plate *a*³ lying close to the recess of the form *b*.

The circular recess *a*¹ around the neck of the button widens toward the interior so 65 that the suction disk *c* after being passed over the head *a*² will slip readily and without friction into place and draw tight around the neck of the button. The large foot-plate *a*³ with its outer rim prevents the 70 rubber disk *c* from resting on the dental-plate and at the same time reduces the free portion of said disk to a reasonable proportion, so as to obviate flabbiness of the outer edge of the suction disk and thus prevents 75 the entering and wedging in of food thereunder and accompanying looseness of the plate.

It will be noted that the construction described may be employed for all shapes of 80 suction-devices, such as round, oval, square, and any other forms.

I am aware that prior to my invention disks for molding the suction cavity on dental-plates have been made with an inserted 85 stud or button to be embedded in the dental-plate. I therefore do not claim such a combination broadly, but

I claim:

1. A disk-like form for molding the suction cavity on dental-plates and embedding the fastening button for the rubber disk thereon, having a recess to receive the head of the fastening button to be embedded on the denture-plate, and the lower edges of 95 the opening to receive large foot plate of the button, substantially as described and for the purpose set forth.

2. The button for the rubber disk to be inserted in the dental plate having an upper and lower larger plate united by a shank with an internally outwardly widening recess between the two plates, substantially as described and for the purpose set forth.

5 In testimony whereof, I have hereunto sub-

scribed my name in the presence of two witnesses.

CARL RAUHE. [L.S.]
